CLAIM

The ornamental design for a grill, as shown and described.

DESCRIPTION

FIG. 1 is a front, left-side isometric view of a grill in accordance with the new design;

FIG. 2 is a front, right-side isometric view thereof;

FIG. 3 is a rear right-side isometric view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines shown in the drawings depict portions of the grill that form no part of the claim. The broken lines act as boundaries of the claim where they intersect claimed surfaces.
